UNITED STATES PATENT OFFICE.

WILLIAM D. DOTY, OF STREATOR, ILLINOIS.

AIR-PURIFYING AND VENTILATING DEVICE.

1,232,511.

Specification of Letters Patent. Patented July 10, 1917.

Application filed July 11, 1916. Serial No. 108,647.

To all whom it may concern:

Be it known that I, WILLIAM D. DOTY, a citizen of the United States, residing at Streator, in the county of La Salle and State 5 of Illinois, have invented certain new and useful Improvements in Air-Purifying and Ventilating Devices, of which the following is a specification.

This invention relates to air purifying 10 and ventilating devices and more particularly a screen designed for arrangement in a window or the like and the invention is designed more particularly as an improvement upon the structure shown in my co- 15 pending application filed Jan. 8, 1916, Serial No. 71,040. In the structure shown in the said copending application the foraminous sheets of the screen are secured in place by engaging their edges with spurs which 20 are carried by the members of the slidably connected frames which comprise the body of the screen but this arrangement has not proven entirely satisfactory inasmuch as the spurs penetrate the material of the said 25 foraminous sheets and, furthermore, are liable to cause injury to one's hands in opening and closing and otherwise manipulating the screen. Therefore, the present invention aims to provide a novel means for 30 securing the foraminous sheets in their respective frames in such manner that they may be readily removed and replaced and will not be liable to become torn or frayed at their edges and also in such manner that 35 no sharp spurs or projections will be presented in position liable to cause injury to one's hands in manipulating the screen.

In the accompanying drawings;—

Figure 1 is a perspective view of the 40 screen embodying the present invention;

Fig. 2 is a view, in elevation thereof, parts being broken away and parts being shown in section, and the said screen being closed;

Fig. 3 is a view looking at the upper edge 45 of the said screen;

Fig. 4 is a horizontal sectional view there- through;

Fig. 5 is a vertical transverse sectional view;

Fig. 6 is a detail horizontal sectional view 50 through the adjacent ends of the frames comprising the screen;

Fig. 7 is a perspective view of one corner 55 of one of the frames, the frame members being separated;

Fig. 8 is a group perspective view illus-

trating one end of one of the frames, one end of the foraminous sheet which is to be arranged therein, and a portion of the flexible binding element for securing the said 60 sheet in place.

The screen consists essentially of two frames which are slidably connected with each other whereby the screen as a whole may be expanded or contracted and therefore be adapted for arrangement within window frames of various sizes and these frames are substantially of counterpart construction. Each frame includes upper and lower side members, indicated by the numerals 1 and 2, respectively, and end members, which are indicated by the numeral 3, the outer vertical edge of each of the end members being overturned upon the said member, as indicated by the numeral 4, so 70 as to reinforce the said member. The opposite or inner vertical edge portion of each of the end members 3 is turned in, as at 5, to form a flange which lies in spaced relation to the face of the said end member and between the said flange and the said member there is in this manner provided a channel 6 for a purpose to be presently explained. Also for a purpose to be presently set forth the edge portion of the flange 5 is bent inwards 75 upon itself, as indicated by the numeral 7, so that the channel 6 is in effect slightly contracted at its open side. The ends of the upper and lower members 1 and 2 of each frame and the upper and lower 80 ends of the end members 3 thereof are overlapped, as clearly shown in the drawings, and secured together by welding, or in any other suitable manner. The inner longitudinal edge portion of each of the members 95 1 and 2 of each frame is bent over as indicated by the numeral 8 so as to form a channel 9 corresponding to the channel 6 and the edge portion of the flange 8 is turned inwards 100 upon the said flange, as indicated by the numeral 10 so that the channels 9 also are slightly contracted or restricted at their open sides. It will be observed by reference to the drawings that the ends of the channels 6 and 9 communicate with each 105 other and therefore each of the frames is provided at one side with a continuous channel which is of rectangular extent, or in other words, extends parallel to the margin of the frame and is spaced inwardly 110 therefrom. A foraminous sheet of material, such for example as cloth, indicated

2
by the numeral 11, is removably arranged within each of the frames and in securing the said sheets in place the marginal portions thereof are laid within the channels 6 and 9 of the respective frame and a suitable length of cord or like flexible and yieldable material is stretched within the channels and extends continuously throughout the length of the respective channel. The 10 flexible binding element 12 serves to bind the marginal portion of the foraminous sheet which it is to secure in place, within the channels 6 and 9, and for this purpose the cord is preferably of a diameter slightly 15 greater than the width of the channel so that when forced into the channel it will be securely frictionally held therein not only by reason of its frictional engagement with the marginal portions of the sheet and with 20 the walls of the channels, but also by reason of its engagement against the overturned edges 7 and 10, as clearly shown in Figs. 4 and 5 of the drawings. In order to prevent insects from passing between the frames 25 comprising the screen, the outer vertical edge portion of the end member of one screen is turned inwardly at right angles to form a guard flange, indicated by the numeral 13, the edge of which flange lies relatively close to the foraminous sheet which is 30 mounted in the other one of the said frames, and in order to slidably connect the frames, the outer longitudinal edge portions of the upper and lower members of one frame are 35 overturned to form guide flanges 14 receiving slidably the outer longitudinal edges of the said upper and lower members of the other frame.

Having thus described the invention, what 40 is claimed as new is:

1. In a device of the class described, a frame having its component members provided with flanges at one side forming a channel extending around the opening defined by the said members, the edge portion of the said flange being turned inwardly

upon itself whereby the channel will be restricted at the open side thereof, a foraminous sheet of material arranged within the frame and having its marginal portions 50 laid within the channel, and a yieldable flexible element also laid within the channel and engaged by the edges of the overturned portions of the said flanges.

2. In a device of the class described, a 55 frame having its component members provided with flanges at one side forming a channel extending around the opening defined by the said members, the free edge portion of each flange being bent upon itself 60 inwardly with the edge of the bent in portion spaced from the bottom of the channel formed by the respective flange whereby the channel will be restricted at its open side and also whereby a shoulder will be provided 65 within the channel extending longitudinally thereof, a flexible foraminous sheet of material arranged within the frame and having its marginal portions laid within the channel, and a yieldable flexible element also 70 laid within the channel and confining the marginal portions of the said sheet of material within the bottoms of the channels and against the said edges of the inturned portions of the flanges. 75

3. In a device of the class described, a frame consisting of plates having their ends secured together and defining a central opening, the outer edges of the plates being doubled on themselves and the inner edges 80 thereof being doubled on themselves in the opposite direction whereby a channel will be provided on one side of the frame around the central opening therein, the free extremities of said inner doubled edges being 85 beaded whereby to contract the mouth of the channel, a sheet of foraminous material having its edges within said channel, and a flexible binding element laid within the channel against the edges of said sheet. 90

In testimony whereof I affix my signature.
WILLIAM D. DOTY. [L. S.]
